UNITED STATES PATENT OFFICE.

ALFRED L. WEISSENTHANNER, OF NEW YORK, N. Y.

BOTTLE-SEALING MACHINE.

No. 894,864.

Specification of Letters Patent.

Patented Aug. 4, 1908.

Application filed April 3, 1905. Serial No. 253,705.

To all whom it may concern:

Be it known that I, ALFRED L. WEISSENTHANNER, a citizen of the Republic of France, and a resident of New York city, State of New York, have invented a certain new and useful Improvement in Bottle-Sealing Machines, of which the following is a specification.

My invention relates to a machine for 10 capping bottles and similar receptacles having an annular shoulder or bead around the head, the object being to construct a machine which shall comprise as an essential feature a chuck or die into which the bottle is forced in such 15 manner as to reshape the cap to conform to the contour of the rim of the bottle, and in which provision is made for all inaccuracies or irregularities in the form and size of caps and bottles liable to be met with in practice. 20 This chuck in the form shown in the drawing is held rigidly against vertical movement, although it may be vertically movable, and is split longitudinally to form a series of spring jaws which will allow of a slight radial yielding movement when a bottle is forced into it, thus securing a uniform and evenly distributed pressure upon the corner of the cap.

A further feature of the invention comprises a crimping or bending tool which operates to circumferentially bend the flange of the cap into locking engagement with the shoulder of the bottle, said tool being arranged relatively to the chuck and its operation being so timed as to effect the desired 35 crimping or bending after the cap has been reshaped and while the bottle is held fast between the table and the chuck.

Another feature of the invention comprises means for concaving the center of the cap.

The invention will be understood by reference to the accompanying drawings in which

Figure 1 is a side elevation of a bottle sealing machine embodying my invention in its preferred form; Fig. 2 is a front elevation 45 with certain of the parts in section; Fig. 3 is a top plan view; Fig. 4 is a detail view of the head of the machine with the frame in section; Fig. 5 is an inverted plan view of the head; Fig. 6 is a vertical section of the head 50 showing the means for closing the crimping tool about the neck of the bottle; Fig. 7 is a top plan view of the head of the machine; Fig. 8 is a sectional view on the plane of the line 8—8 of Fig. 6 looking in the direction of the arrow; 55 Fig. 9 is a detail view showing the bottle neck and chuck in position before sealing; Fig. 10

is a similar view showing the parts in position after sealing; Fig. 11 is a view partly in vertical section and partly in elevation illustrating the head of the machine of Fig. 1 with an addition, said addition comprising 60 means for depressing the center of the cap after the sealing operation. Fig. 12 is a detail in vertical section to illustrate the operation of the depressing device of Fig. 11.

Referring to the drawings the numeral 1 designates the frame of the machine in the form of a casting which is provided at its lower part with a bearing for a shaft 2 which shaft is also supported in a bearing in a 65 standard 3. Pivotedly supported on a shaft 5 in the lower part of the frame is a treadle 4, the rear end of which, when depressed, is adapted to strike against the under side of an arm 6 secured to a rock shaft 7. On this 70 rock shaft is an arm 8 (Figs. 1 and 3) the upper end of which is U-shaped and engages a collar 9 on a clutch 9' slidably keyed on shaft 2. This clutch, when the treadle is depressed, is moved so as to bring pulley 11 75 into operative engagement with the shaft 2 whereby the latter is rotated from the power shaft by a belt passing around the pulley 11.

Supported in bearings in the frame 1 is a 80 shaft 12 on which is pivotally mounted a lever 13 the forward end of which is forked (Fig. 2) and upon which rests a sleeve 14 supported in tubular extensions 15 of the frame 1. Passing longitudinally through 85 said sleeve is a spindle 16 which is surrounded by the forked ends of lever 13 but not in engagement therewith. The spindle 16 carries at its upper end a table 17 adapted to receive the bottle to be capped, and said table 90 may be provided with a gage 18 for the proper centering of the bottle. Clamped to spindle 16 is a split collar 19 between which and the lower wall of the sleeve 14, and surrounding the spindle 16, is a spring 20 which acts as a cushion when the bottle is forced 95 upward against the chuck.

Integral with the treadle 4 is an upwardly 100 projecting arm 21, which, when the treadle is depressed, acts against an arm 22 depending from lever 13 thereby rocking said lever 105 and elevating its forward end and raising the sleeve 14, and through the spring 20 also raising the spindle 16 so as to bring the bottle with relation to the chuck to about the position shown in Fig. 9. The rear end of 110 lever 13 supports a roller 23 which is adapted to be acted upon by a cam 24 fast on the

shaft 2. When the treadle 4 is depressed, the roller 23 is moved away from the face of cam 24 a short distance but not far enough to escape the path of said cam.

5 As stated above the depression of treadle 4 raises the bottle into about the position shown in Fig. 9, the cam 24 then acting upon roller 23 will deliver a sudden blow so as to cause the lever 13 to further raise the sleeve 14 and to forcibly project the bottle against the chuck. As cam 24 wipes from off the roller 23, the weight of sleeve 14 is sufficient to rock lever 13 so as to bring the roller 23 into contact with the face of cam 24, and to 10 rock the treadle 4 through the arms 22 and 21 to restore it to its normal position. A spring 25 secured to the arm 6 will move the clutch in a reverse direction so as to release the pulley 11 and the machine will come to a 15 position of rest.

Formed integral with the frame 1 is a head 26 bored longitudinally in alignment with the spindle 16 and adapted to support the chuck and the bending tool. The head 26 is formed 25 with four inwardly projecting lugs 27 which permit of the free passage between them of a spindle 28. To the under side of the lugs 27 are bolted brackets 29 which are formed integral with a steel ring 30 which surrounds the 30 spindle 28, said ring being clamped about said spindle by a collar 31 which is forced between said ring and the inner walls of the lugs 27. The spindle 28 is screw-threaded for a portion of its length to receive a jam nut 32 which is forced up against the lower end of the ring 30. The ring 30 is also screw-threaded and adapted to engage the threaded portion of the spindle 28 so that said spindle may be adjusted vertically although held 35 rigidly against vertical movement when once adjusted. The lower end of the spindle 28 is reamed out to form a sleeve 33. The spindle is of steel and said sleeve is split longitudinally to provide a plurality of radially yielding spring jaws 33' having at the inner sides of their lower ends suitable concaved working faces. The sleeve 33 constitutes in effect a chuck and will be so referred to. When the bottle is forced upward these working 40 faces receive the corner of the cap.

The inner diameter of the chuck formed by the jaws 33' is substantially equal to the diameter of the rim of the smallest bottle liable to be met with in practice within the 45 range of probable variations of size and shape. The function of the chuck is that of the female member of a die so that under the pressure applied to the bottle acting as a punch a uniform and evenly distributed 50 pressure will be applied about the corner of the cap to reshape it and to cause it to conform exactly to the rim of the bottle.

The present machine is designed not only to reshape the cap of the bottle but to bend 55 the flange of the cap into secure locking en-

gagement with the shoulder on the neck of the bottle. The mechanism for accomplishing the latter object of the invention is as follows:—Having a loose bearing on a stationary shaft 70 (see Fig. 1) is a lever 34 one arm of which carries a roller 35 held in contact with the face of a cam 36, fast on the shaft 2, by a spring 37 secured to the other arm of said lever and to a fixed stud on the frame. The other arm of lever 34 is secured 70 to one end of a vertical rod 38 the upper end of said rod being pivotally hung to a stirrup 39 encircling and secured to a lever 40, said lever 40 being pivoted on a shaft 41 having bearings in the frame. The forward end of 80 lever 40 is forked (Figs. 1 and 3), and in slots 41 formed in the projecting arms are supported lugs 42 integral with a sleeve 43. The spindle 28 projects into said sleeve in the vertical movements of the latter. The lower 85 end of sleeve 43 is formed with a cam face 44 adapted to operate a sectional flange bending tool which is constituted of a series of jaws 45 each having an inwardly projecting shoulder 46 made with a more or less sharp crimping edge 47. These jaws 45 are struck on the arc of a circle and when assembled constitute a bending tool adapted to bend the flange of a sealing cap into locking engagement with a shoulder on the bottle 90 head. Each jaw is formed with a shoulder on its inner upper wall adapted to engage a collar 48 secured to the spindle 28, the latter being centrally disposed within the bending tool. To the outer side of each jaw 45 is secured, by means of a screw bolt, the lower 100 end of a spring arm 49, said springs being bowed outwardly (Figs. 4 and 6) and tightly clamped at their upper ends between the ring 30 and collar 31 (Fig. 6). The normal 105 positions of the jaws 45 is such as to leave a space between contiguous edges so as to permit their lower ends to be moved inwardly to form a practically closed circle about the neck of the bottle when pressure is applied 110 to the sides of the spring arms 49. The crimping edge 47 may be smooth or knurled, and a greater or less number of jaws than that shown in the drawings may be arranged. This closing in of the jaws of the bending 115 tool is effected by cam 44 through levers 50 pivoted on studs 51 secured to the contiguous walls of brackets 29 (Figs. 4 and 8). The levers 50 carry at their upper ends rollers 52 and at their lower ends are formed with 120 threaded eyes 53 to receive adjustable bolts 54 which bolts project into close proximity to the bowed sides of spring arms 49. These parts are so adjusted that as the sleeve 43 is moved downward on the spindle 28 the cam 125 44 will contact with rollers 52 thereby rocking levers 50 and forcing the bolts 54 against the spring arms 49 to close the jaws 45 of the bending tool about the neck of the bottle.

The operation of the machine will be read- 130

ily understood from the foregoing description. The cams 24 and 36 are so disposed on the shaft 2 relative to each other that the former acts upon lever 13 to force the bottle 5 into the chuck 33 before cam 36 acts upon lever 34 to lower the cam 44. As above stated, when the treadle 4 is depressed the sleeve 14 is moved vertically a sufficient distance to carry the bottle, upon which a cap 10 55 has been previously placed, into substantially the position shown in Fig. 9. Such movement of the treadle also moves the roller 23 away from, but not out of the path of, cam 24 so that as said cam is rotated a sharp 15 blow will be delivered against roller 23 to impart a further vertical movement to sleeve 14, thereby forcibly impinging the top of the bottle against the chuck, the plane of impact extending over the corner of the cap 55. The 20 internal diameter of the face of the chuck and its configuration are such, relatively to a standard shape and size of bottle and cap, as to effect a reshaping of the cap into exact conformity with the rim of the bottle. The 25 sealing disk 56 on the under side of the cap is compressed over the rim and the metal of the crown of the cap formed into a slightly convexed form. The spring 20 inclosed within sleeve 14 takes the force of the impact of the 30 bottle against the chuck and prevents breakage. Although the chuck is held rigid against vertical movement the capability of radial expansion of the jaws 33' of the chuck, provides for all variations from a standard 35 shape and size thereby securing uniformity of pressure circumferentially around the corner of the cap. After cam 24 has thus acted to effect the compression and reshaping of the cap, the cam 36 acts to raise the outer end 40 of lever 34 thereby depressing lever 40 and bringing the cam face 44 down against the rollers 52 and rocking levers 50 on their pivots. The inward movement of the bolts 54 45 against spring arms 49 effects a closing-in movement of the jaws 45 against the flange 57 of the cap, the crimping edge 47 formed by the several shoulders 46 being practically continuous around the bottle neck. The upward movement of the bottle brings the 50 shoulder 58 in such position that the inward movement of the jaws 45 will cause the edge 47 to bend the flange of the cap into secure locking engagement with said shoulder as indicated in Fig. 10. Owing to the manner of 55 supporting the jaws 45 they are capable not only of a radial movement but also a vertical displacement downward due to the flexing of the spring arms 49, so that notwithstanding irregularities in the size and shape of the 60 bottle shoulders and caps the edge 47 will always be brought into a position to effect the bending of the cap flange 57 under the shoulder. Thus if the height of the shoulder should be greater than the normal or stand- 65 ard the edge 47 will strike the shoulder at

some point between its middle and lower circumferential lines and the jaws 45 will accommodate themselves to such variation by sliding over the curved under side of the shoulder so as to bend the flange into proper 70 locking engagement with the shoulder. The length of levers 50 is so proportioned that the bolts 54 strike a little above the center of the bowed portions of spring arms 49 to permit of this slight downward movement of the 75 jaws 45 and to effect the desired inward radial movement of said jaws.

It will be understood that the extent of the movements of the jaws 45 is very small, being merely sufficient to effect the desired 80 bending of the cap flange into intimate locking engagement with the shoulder.

When the high point of cam 36 wipes from under roller 35, spring 37 acts to raise cam 44 through rod 38 thereby releasing the 85 spring arms 49 and permitting the jaws 45 to resume their normal positions. During the crimping operation the cam 24 maintains the bottle pressed against the chuck and as soon as the crimping is completed said cam wipes 90 from off the roller 23 thus permitting the sleeve 14 to fall, said sleeve in its descent rocking the lever 13 until the arm 22 impinges against the arm 21 of the treadle 4, the latter being held in its depressed position 95 by a suitable stop. The bottle then being free may be removed from the machine.

The yielding characteristic of the jaws of both the chuck and the bending tool permits them to give sufficiently and to prevent the 100 breaking or crushing of the bottle, and to accommodate variable sizes and shapes of bottles and caps.

In Figs. 11 and 12 I have shown a modification or addition to the machine. In this 105 modification the spindle 28 is bored longitudinally throughout its length but fixedly supported against vertical movement as described heretofore. The sleeve 43 which carries cam 44 is open at the top, and through said opening and passing longitudinally through spindle 28 to near the face of the chuck 33 is a plunger 59, said plunger being supported by a spring 60 surrounding its head and bearing against the top of sleeve 110 43 and a nut 61 carried by the plunger. Pivotaly supported on the shaft 41 is a forwardly projecting arm 62 the outer end of which is provided with a hammer head 63 suspended above the plunger 59 and adapted to deliver a blow thereto when lever 40 is depressed by cam 36. Near one end of lever 40 is secured a shoe 64 adapted to engage the under side of a lug 65 projecting from a plate 66 which plate is supported upon screw bolts 115 67 tapped into arm 62. As shown in Fig. 11 the lever 40 is in its raised position thus supporting arm 62 in a position to deliver its blow. When lever 40 is depressed the shoe 64 is moved from under lug 65 and through 120 66

125 130

the spring connection 68, arm 62 is moved downward and a blow delivered by hammer 63 to plunger 59, the parts being so proportioned that the plunger will strike the crown 5 of the cap at or immediately after the time of operation of the bending tool by cam 44. The lower end of plunger 59 is convexed as shown and the diameter of the striking face is such as to concave the crown of the cap as 10 shown in Fig. 12, thus effecting a thoroughly efficient seal. An adjustable stop 69 secured to a lug on arm 62 limits the downward movement of arm 62 so that shoe 64 on its return movement will be held in a position to 15 sustain arm 62. The plate 66 may be slotted as shown in the drawing so as to adjust the position of lug 65 relative to said shoe.

What I claim and desire to secure by Letters Patent is:—

20 1. In a bottle sealing machine the combination of a bottle support, a chuck rigidly held against vertical movement, means to raise said support to force the bottle into engagement with said chuck, and a non-rotary 25 flange - bending tool circumjacent the cap flange.

2. In a bottle sealing machine the combination of a yielding bottle support, a chuck rigidly held against vertical movement, 30 means to force the bottle into engagement with said chuck, and a non-rotary flange-bending tool circumjacent the cap flange.

3. In a bottle sealing machine the combination of a bottle support, a chuck rigidly 35 held against vertical movement, means to raise said support to force the bottle into engagement with said chuck, said chuck having a central bore and the walls thereof split longitudinally so as to provide an adjustable 40 working face adapted to receive the impact of the bottle about the overlying corner of the cap.

4. In a bottle sealing machine the combination of a bottle support, a chuck rigidly 45 held against vertical movement, means to raise said support to force the bottle into engagement with said chuck, said chuck having the walls thereof split longitudinally so as to provide an adjustable working face adapted 50 to receive the impact of the bottle about the overlying corner of the cap.

5. In a bottle sealing machine the combination of a bottle support, a chuck, a tool 55 adapted to bend the flange of a sealing cap into locking engagement with the bottle head, said tool comprising a plurality of vertically and radially yielding jaws.

6. In a bottle sealing machine the combination of a bottle support, a chuck, means to 60 force the bottle into engagement with said chuck, a tool adapted to bend the flange of a sealing cap into locking engagement with the bottle head, said tool comprising a plurality of vertically yielding compression jaws.

65 7. In a bottle sealing machine the combi-

nation of a bottle support, a chuck, means to force the bottle into engagement with said chuck, a tool adapted to bend the flange of a sealing cap into locking engagement with the bottle head, said tool comprising a plurality of vertically and radially yielding compression jaws.

8. In a bottle sealing machine the combination of a bottle support, a radially yielding chuck, a tool adapted to bend the flange of a 75 sealing cap into locking engagement with the bottle head, said tool comprising a plurality of yielding jaws.

9. In a bottle sealing machine the combination of a bottle support, a radially yielding 80 chuck, a tool adapted to bend the flange of a sealing cap into locking engagement with the bottle head, said tool comprising a plurality of vertically yielding jaws.

10. In a bottle sealing machine the combination of a bottle support, a radially yielding 85 chuck, a tool adapted to bend the flange of a sealing cap into locking engagement with the bottle head, said tool comprising a plurality of radially yielding jaws.

90 11. In a bottle sealing machine the combination of a bottle support, a radially yielding chuck, a tool adapted to bend the flange of a sealing cap into locking engagement with the bottle head, said tool comprising a plurality of vertically and radially yielding jaws.

12. In a bottle sealing machine the combination of a bottle support, a radially yielding chuck, means to force the bottle into engagement with said chuck, a tool adapted to 100 bend the flange of a sealing cap into locking engagement with the bottle head, said tool comprising a plurality of vertically yielding compression jaws.

13. In a bottle sealing machine the combination of a bottle support, a radially yielding 105 chuck, means to force the bottle into engagement with said chuck, a tool adapted to bend the flange of a sealing cap into locking engagement with the bottle head, said tool comprising a plurality of radially yielding compression jaws.

110 14. In a bottle sealing machine the combination of a bottle support, a radially yielding chuck, means to force the bottle into engagement with said chuck, a tool adapted to bend the flange of a sealing cap into locking engagement with the bottle head, said tool comprising a plurality of vertically and radially yielding compression jaws.

115 15. In a bottle sealing machine the combination of a bottle support, a chuck, means to force the bottle into engagement with said chuck, a tool adapted to bend the flange of a sealing cap into locking engagement with the 120 bottle head, said tool comprising a plurality of yielding compression jaws.

16. In a bottle sealing machine the combination of a bottle support, a chuck, means to force the bottle into engagement with said 125

chuck, a tool adapted to bend the flange of a sealing cap into locking engagement with the bottle head, and means permitting the said chuck and tool to yield vertically relative to

5 each other during the sealing operation.

17. In a bottle sealing machine the combination of a bottle support, a chuck having radially yielding jaws, means to raise said support to force the bottle into engagement 10 with said chuck, a bending tool comprising yieldingly supported compression jaws, and means to compress said jaws against the cap flange for the purpose described.

18. In a bottle sealing machine the combination of a bottle support, a chuck having radially yielding jaws, means to hold said chuck rigidly against vertical movement, means to raise said support to force the bottle into engagement with said chuck, a bending 20 tool comprising yieldingly supported compression jaws, and means to compress said jaws against the cap flange for the purpose described.

19. In a bottle sealing machine the combination of an annular bending tool adapted to bend the flange of a sealing cap into locking engagement with a bottle head, a chuck and means to force the bottle into the same, means for holding said chuck rigidly against 30 vertical movement and centrally with relation to said tool, the latter having a bearing on said chuck; and means for forcing said tool against the cap flange.

20. In a bottle sealing machine the combination of a chuck into which the bottle is adapted to be forced, a non-rotary tool adapted to bend the flange of a sealing cap into locking engagement with the bottle head said tool comprising a plurality of compression 40 jaws, spring arms upon which said jaws are supported, and means for flexing said arms to force the jaws of the bending tool against the cap flange below the chuck.

21. In a bottle sealing machine the combination of a chuck into which the bottle is adapted to be forced, a bending tool adapted to bend the flange of a sealing cap into locking engagement with the bottle head said tool comprising a plurality of compression 50 jaws, spring supports for said jaws, and means to control the vertical yielding movement of said supports in a downward direction.

22. In a bottle sealing machine the combination of a non-rotative bending tool adapted to bend the flange of a sealing cap into locking engagement with a bottle head, said tool comprising a plurality of compression jaws, spring arms upon which said jaws are supported, pivotally suspended levers having 60 one end in proximity to said arms, and means

for moving said levers against said arms to flex the same to effect the compression of the jaws of the bending tool against the cap flange.

6

23. In a bottle sealing machine the combination of a chuck the spindle of which is fixedly supported and into which chuck the bottle is adapted to be forced, a non-rotary tool adapted to bend the flange of a sealing 70 cap into locking engagement with a bottle head, said tool comprising a plurality of compression jaws circumjacent said flange, a cam slidably mounted on the chuck spindle, and means actuated by said cam to compress the 75 jaws of the bending tool against the cap flange.

24. In a bottle capping machine, a presser block adapted to bear upon the top of the cap, means below said presser-block for applying a substantially equal constricting pressure around the periphery of the flange of the cap, and means for operating said constricting means progressively axially of the cap.

80

25. In a bottle capping machine, a presser block adapted to bear upon the top of the cap, means for applying a substantially equal constricting pressure around the periphery of the flange of the cap and means for first 90 transversely operating said flange constricting means to engage said flange and then moving said flange constricting means axially of the cap.

26. In a bottle capping machine, the combination with a presser-head adapted to bear upon the top of the cap, and means for securing the flange of the cap to the bottle, of means for causing said securing means to operatively engage the cap-flange, and means 100 for moving said securing means while in operative engagement with the cap flange in a direction axial of the bottle.

27. In a bottle capping machine, the combination with a presser head adapted to bear 105 upon the top of the cap, and means for securing the flange of the cap to the bottle, of means for causing said securing means to operatively engage the cap flange and for maintaining said securing means in said operative engagement, and means for moving said securing means while in operative engagement with the cap flange in a direction 110 axial of the bottle.

In witness whereof I have hereunto signed 115 my name in the presence of two subscribing witnesses.

ALFRED L. WEISSENTHANNER.
